Attorney

UNITED STATES PATENT OFFICE.

CESARE SONCINI, OF BRESCIA, ITALY, ASSIGNOR TO SOCIETA ITALIANA ERNESTO BREDA, OF MILAN, ITALY, A JOINT-STOCK COMPANY.

SAFETY LOCK FOR AUTOMATIC FIREARMS.

Application filed June 17, 1926, Serial No. 116,660, and in Italy June 20, 1925.

The present invention relates to a safety device so constructed and arranged as to prevent the release of the firing-pin before the breech-block reaches full closing position; such device comprising a spring-actuated member having a locking tooth which normally holds the pin against operation but which is automatically disengaged by the block when, and only when, the latter completes its closing stroke or movement.

In the accompanying drawing, Figure 1 is a fragmental longitudinal section of an automatic fire-arm equipped with the invention, the parts being shown in the positions which they occupy at the moment when the breech-block reaches the end of its closing movement and the firing-pin is released and just about to commence its stroke; and Figs. 2 and 3 are enlarged detail views in perspective of the safety device and breech-block, respectively.

Referring more particularly to the drawing, 5 indicates the breech-block, and 6 the firing-pin. The upper part of the block has formed in it a longitudinal slot 5' which extends almost to the rear end thereof and opens throughout its entire length into the bore of the block; the top face of the block at the extreme rear end of the slot comprising a pair of upwardly and rearwardly inclined surfaces 3' (Fig. 3) which are disposed at opposite sides of the slot.

The locking or safety device 1, best shown in Fig. 2, is mounted to slide vertically in a suitable housing located above the slot 5' in the breech-block 5, and is provided at its lower end with a tooth 2 which directly alines with said slot, so that it normally tends to enter the same, due to the downward pressure imposed upon the locking slide by a spring 4 as represented in Fig. 1. A pair of wings 3 is also provided upon the bottom of the slide at opposite sides of tooth 2, and these wings are positioned to be struck by the inclined surfaces 3' on the breech-block so as to coat therewith in raising the slide against the pressure of spring 4; for which purpose, the under faces of the wings are likewise inclined in conformity with the aforesaid surfaces 3', so that the effect is that of two coacting pairs of cams. It will be recalled, however, that the cams 3' are located substantially at the rear end

of the breech-block, so that they will not engage the cams 3 until the breech-block completes its forward movement.

Finally, the firing-pin 6, which is movable through the bore of the breech-block as usual, is provided upon its upper surface with an upstanding tooth 6', likewise arranged in position to project into and travel through the breech-block slot 5', and to directly engage the locking tooth 2.

Assuming, then, that the breech-block and firing-pin are retracted, the tooth 6' will be located at the front end of slot 5' and will be engaged and held by the tooth 2 on the locking slide 1, which latter, at that time, is depressed to its full extent by spring 4. Hence, when the breech-block moves forward to close the breech, the firing-pin remains locked in its retracted or cocked position, due to the engagement of teeth 6' and 2; but just as the block completes its closing stroke, however, its cams 3' hit against the under surfaces of the wings 3 on the locking slide 1 and lift the same far enough to disengage tooth 2 from tooth 6', this being the precise position illustrated in the drawing. Then—and not until then—the firing-pin is released and is free to make its active stroke in the usual way when the gun is fired.

I claim as my invention:

1. In an automatic fire-arm, in combination, a sliding breech-block having an axial bore extending through it, and a longitudinal slot in its upper portion opening into such bore; a firing-pin movable through said bore; a safety device having a locking part projecting through said slot and normally engaging the firing-pin to hold it in retracted position; and means for automatically disengaging said locking part from said firing-pin at the moment the breech-block reaches fully-closed position.

2. In an automatic fire-arm, in combination, a sliding breech-block having an axial bore extending through it, and a longitudinal slot in its upper portion opening into such bore; a firing-pin movable through said bore; a spring-pressed safety slide having a locking tooth which projects through said slot and normally engages the firing-pin to hold it in retracted position; and means for automatically raising said slide to disengage its tooth from the firing-pin.

at the moment the breech-block completes its closing stroke.

3. An arrangement according to claim 2, in which the firing-pin has an upstanding tooth that is normally engaged by the tooth on the safety slide.

4. In an automatic fire-arm, in combination, a sliding breech-block having an axial bore extending through it, and a longitudinal slot in its upper portion opening into such bore; a firing-pin movable through said bore; a safety device having a locking part projecting through said slot and normally engaging the firing-pin to hold it in retracted position; and coacting means on the breech-block and safety device for automatically disengaging said locking part from said firing-pin at the moment the breech-block reaches fully-closed position.

5. In an automatic fire-arm, in combination, a sliding breech-block having an axial bore extending through it, and a longitudinal slot in its upper portion opening into such bore; a firing-pin movable through said bore; a safety device having a locking part projecting through said slot and normally engaging the firing-pin to hold it in retracted position; and coacting cam means on the breech-block and safety device adapted to strike each other at the moment the breech-block reaches fully-closed position so as to disengage said locking part from said firing-pin.

6. In an automatic fire-arm, in combination, a sliding breech-block having an axial bore extending through it, and a longitudinal slot in its upper portion opening into such bore; a firing-pin movable through said bore; a spring-pressed safety slide having a locking tooth which projects through said slot and normally engages the firing-pin to hold it in retracted position; and coacting means on the breech-block and safety slide for automatically lifting the latter at the moment said breech-block reaches fully-closed position so as to dis-

engage the tooth on said slide from the firing-pin.

7. In an automatic fire-arm, in combination, a sliding breech-block having an axial bore extending through it, and a longitudinal slot in its upper portion opening into such bore; a firing-pin movable through said bore; a spring-pressed safety slide having a locking tooth which projects through said slot and normally engages the firing-pin to hold it in retracted position; and coacting cam means on the breech-block and safety slide adapted to strike each other and thereby lift the slide, at the moment said breech-block reaches fully-closed position so as to disengage the tooth on said slide from the firing-pin.

8. In an automatic fire-arm, in combination, a sliding breech-block; a firing pin; a spring-pressed safety device having a locking part which normally engages the firing-pin to hold it against movement; and coacting means on said safety slide and breech-block for automatically disengaging said locking part from the firing-pin at the moment the breech-block reaches fully-closed position.

9. In an automatic fire-arm, in combination, a sliding breech-block; a firing pin; a spring-pressed safety device having a locking tooth which normally engages the firing-pin to hold it against movement, and also having a pair of cams arranged at opposite sides of such tooth; and a pair of cams at the rear end of the breech-block to engage the first-named cams at the moment said breech-block reaches fully-closed position so as to lift the safety device and thereby release its tooth from the firing-pin.

10. An arrangement according to claim 9, in which the firing-pin is provided at its rear end with an upstanding projection which is normally engaged by the locking tooth on the safety device.

In testimony whereof I affix my signature.
CESARE SONCINI.
